Lacy Lacy, Attorneys

UNITED STATES PATENT OFFICE.

HAROLD H. DE MOSS, OF CLARKSBURG, WEST VIRGINIA.

RAIL TIE.

Application filed December 23, 1921. Serial No. 524,380.

To all whom it may concern:

Be it known that I, HAROLD H. DE MOSS, a citizen of the United States, residing at Clarksburg, in the county of Harrison and State of West Virginia, have invented certain new and useful Improvements in Rail Ties, of which the following is a specification.

This invention relates to improvements in metallic rail ties and more particularly to an improved rail tie for use in laying temporary tracks in mines. In laying such tracks it has heretofore been the custom to employ ties having spaced upstanding members at their ends against and beneath one of which the rail is disposed at one side, a wooden wedge being driven between the rail and the other said member so as to bind and clamp the rail to its seat. However the preparation of these wedges requires considerable time and labor and their use is generally unsatisfactory. On the other hand it is undesirable to employ rails embodying rail clamping members which require to be secured in place by bolts and nuts as too much time is consumed in assembling and laying the track. Therefore it is the primary object of the present invention to provide a rail tie for use in a temporary track structure which tie will be simple and substantial in structure, will be adapted to securely clamp the rail base without the employment of wooden or other wedges as is now customary, and will be adapted to have its component parts readily and quickly assembled and disassembled thus permitting of the track being laid or taken up in a short space of time.

Where wooden wedges are employed as above mentioned or where the rail clamping members are secured in place by bolts and nuts, wedges of a certain size and shape must be produced in large numbers and because of their nature they soon become so damaged or mutilated as to become unfit for further use. The employment of bolts and nuts is an expensive proposition where they require to be frequently removed and replaced as the threads soon become worn, and also difficulty is often experienced in removing the bolts if they have become rusted. Therefore the invention has a further and equally important object to provide a rail tie of the class referred to embodying a rail clamping member adapted to be secured in

place by an inexpensive and readily obtainable medium, namely an ordinary rail spike adapted to be quickly driven into place to secure the rail clamping member and to be as readily and quickly displaced to release the member when occasion requires.

In the accompanying drawings:

Figure 1 is a plan view of one of the ties embodying the invention in use;

Figure 2 is a detail vertical longitudinal sectional view through one end of the tie and the rail secured thereon;

Figure 3 is a horizontal sectional view through the tie illustrating the means provided for securing the clamping member in clamping position, the view illustrating the manner in which this means is to be employed; and

Figure 4 is a perspective view of one end of the tie, the rail clamping member thereof being separated from the body of the tie.

While the tie embodying the invention may be employed as a permanent rail tie or in other words as a component part of a permanent track, it is primarily designed for use in constructing a temporary track, the tie being indicated in general in the drawings by the numeral 1 and the rails by the numeral 2. The tie 1 comprises a body which is indicated by the numeral 3 and is preferably of channel iron construction, embodying a supporting top portion 4 and depending longitudinal flanges 5 designed to rest upon or seat in the temporary road bed. Near each end the body 3 is provided upon its supporting top portion 4 with a permanent or fixed rail base engaging member indicated by the numeral 6 and comprising an attaching portion 7 riveted or otherwise secured as at 8 to the said portion 4 of the tie body, and a lip 9 which is inclined upwardly from the attaching portion 7 in the direction of the adjacent end of the body and in spaced relation to the upper surface of the said portion 4 so as to receive beneath it the base flange of the rail as best shown in Figure 2 of the drawings.

Each tie further embodies a displaceable or removable rail clamping member which is indicated in general by the numeral 10 and this member comprises a shank 11 which is of dimensions to be fitted into the end of the channel of the body 3 of the tie, seating between the flanges 5 and bearing at its upper side against the under side of the sup-

porting top portion 4 of the said body. At one end the shank 11 is provided with an upwardly and inwardly directed base flange engaging lip 12 designed to overlie the outer 5 flange of the rail base and the adjacent end of the supporting top portion 4 of the tie body as illustrated in Figure 2 of the drawings. Thus it will be seen that in assembling the parts the base flange of the rail is 10 disposed at its inner side beneath the lip 9 of the member 6 and resting upon the supporting top portion 4 of the tie body after which the member 10 is disposed in position with its shank 11 seating within the channel of the body and with the lip 12 engaging about the end of the portion 4 of the body and over the outer side of the rail flange.

In order that the member 10 may be secured in place in a manner to securely grip the rail and hold it to the tie, the flanges 5 are formed, near the ends of the body of the tie with one or more pairs of oppositely located rectangular openings 13, and the 25 shank 11 of the member 10 is formed with transversely extending rectangular openings or bores 14 the ends of which are to be brought into substantial registration with the openings 13. When the member 10 has 30 been disposed in place substantially as illustrated in Figure 3 of the drawings and before being secured, the ends of one of its openings or bores 14 will to a greater or less extent overlap the openings 13, and 35 while the parts are in this position the shank of an ordinary spike indicated by the numeral 15 and having the usual wedge point 16, is driven through one of the openings 13 and into the corresponding opening 14 40 and as the spike is driven into place its wedge end will act upon the wall of the opening 14 to draw the member 10 longitudinally within the channel of the body 3 so that its lip 12 will be caused to firmly bind upon 45 the base flange of the rail. When the spike has been driven into place for the full length of its shank, it will extend through the opening 14 and through both of the openings 13 and the parts will thus be secured 50 locked in place although capable of ready disassembly by simply driving out the spike. It will be understood that while an ordinary rail spike is employed as a locking element in the structure embodying 55 the invention, it constitutes in effect a key having a shank of uniform dimensions throughout its entire length except at its entering end where it is of wedge shape. It will also be evident that the member 10 is 60 more or less resilient and that a sufficient clearance is left at the point where the bend in the lip 12 engages about the end of

the supporting top portion 4 of the tie body and the edge of the rail base flange, to permit of the longitudinal displacement of the 65 member in an inward direction to an extent to insure of proper wedging engagement of the lip 12 with the base flange of the rail.

By providing one or more pairs of the openings 13 and either a single one of the 70 openings 14 or several of the latter openings, if found expedient, the tie is adapted for the support of rails of different sizes but this is of course optional and it may be found the better practice under ordinary 75 conditions to provide a single pair of the openings 13 and a single one of the openings 14.

Having thus described the invention what is claimed as new is:

1. A rail tie for a temporary track comprising a channeled body, a relatively fixed rail base flange engaging member thereon, a rail base flange clamping member comprising a shank disposed within the channel of 85 the body and provided with a base flange engaging lip extending over and above the end of the body, and a securing element removably inserted through the walls of the channel and through the said shank. 90

2. A rail tie for a temporary track comprising a channeled body, a relatively fixed rail base flange engaging member thereon, a rail base flange clamping member comprising a shank disposed within the channel 95 of the body and provided with a base flange engaging lip extending over and above the end of the body, and a securing element removably inserted through the walls of the channel and through the said shank, the 100 said securing element comprising a shank of substantially uniform dimensions except at its entering end where it is of wedge formation to adapt it to exert a wedging action against the clamping member to draw the 105 same into clamping engagement with the rail when the said securing element is driven into place.

3. A rail tie for a temporary track comprising a channeled body, a relatively fixed rail base flange engaging member thereon, and a rail base flange clamping member comprising a shank disposed within the channel of the body and provided at one end with a base flange engaging lip to extend 115 about and above the end of the body to engage the base flange of the rail, the said shank and the walls of the channel being formed with openings for the reception of an ordinary rail spike to serve as a securing 120 means for the parts.

In testimony whereof I affix my signature.

HAROLD H. DE MOSS. [l.s.]
